BLANK-CREASING MACHINE

George W. Swift, Jr., Bordentown, N. J., assignor
to George W. Swift Jr., Inc., Bordertown, N. J.,
a corporation of New Jersey

Application June 13, 1933, Serial No. 675,535

20 Claims. (Cl. 93—58)

This invention relates more especially to the general type of blank-creasing machines shown and described in U. S. Patent No. 1,408,486 which was granted in my name under date of 5 March 7, 1922.

The primary object of my invention is to provide an improved construction and arrangement of parts in a machine of this character to facilitate its adjustment for different kinds of work; to increase the accuracy with which the blanks may be delivered to the creasing or scoring units and maintained in proper registry in respect to the operations to be performed thereon. For this purpose, my invention contemplates a series of paired feed rolls which operate in timed relation to the movements of the blank-creasing units to which they deliver the blanks past a gage roller which may be suitably spaced from the intake end of one of the creasing units to insure the proper delivery of the blank at high velocity.

One of the objects of my present invention is to provide an improved construction for creasing mechanism suitable for receiving blanks from and to be driven in timed relation with the blank-creasing, -slotting and -printing machine shown in my copending application Serial No. 669,156, which was filed in my name under date of May 3, 1933.

30 Another object of my invention is to provide
in a machine for producing parallel creases in
a blank of corrugated board, means of improved
construction for permitting the bodily sidewise
shifting of a plurality of creasing sets with re-
35 ference to one another and for adjusting and
maintaining said sets in various angular rela-
tions to each other in respect to convergence
for the purpose of securing parallelism of the
scorings produced in different kinds of work.

40 Another object of my invention is to provide an improved construction for at least one of the cooperating opposed lines of groove and tongue members which comprises a series of alternately arranged fixed axis rolls and fixed shoes.

45 One of the particular objects of my invention
is to provide a power-transmitting connection
of improved construction between a power shaft
rotatable about a fixed axis and a driven shaft
journalled in an adjustable frame which car-
50 ries a sprocket chain whose links comprise one
of the cooperating opposed lines of scoring mem-
bers in a machine for forming longitudinal
creases in a blank.

In the drawings which exemplify my invention in a preferred embodiment,

Figure 1 is a side elevation of a creasing machine constructed in accordance with the principles of my present invention.

Figure 2 is an enlarged vertical section of the creasing units, parts being broken away and parts shown in elevation. 60

Figure 3 is a top plan view of the central portion of Figure 1.

Figure 4 is a horizontal section of the machine corresponding to line 4-4 of Figure 2.

Figure 5 is an enlarged vertical section of the right-hand side of the machine corresponding to line 5—5 of Figure 2.

Figure 6 is a horizontal detailed section on the line 6-6 of Figure 2.

Figure 7 is a reduced section on the line 7-7 of Figure 2.

Figure 8 is a detached perspective view of one of the grooved creaser members.

Figure 9 is an enlarged perspective view of 75 one of the creaser shoes removed.

According to the present embodiment of my invention, each of a pair of laterally spaced fixed side frames 1 and 2 is provided at the top with a track bar 3 (see Figure 5). Each of said track bars is suitably formed to provide laterally spaced rails 4 for guiding the carrying wheels or rollers 5 of a truck frame which carries the blank-creasing mechanism to be hereinafter described. Said truck frame or carriage comprises laterally spaced side frames, each made up of a channel bar 6, a channel bar 7, a side plate 8 and a top rail 9 of L-shaped cross-section. The several parts of each side frame are bolted together in the manner indi-

frame are bolted together in the manner indicated in Figure 5. The side frames of the carriage are united at the top by spaced transverse guide bars 10 and at the bottom by spaced transverse guide bars 11, fragmentary portions of said guide bars being illustrated in cross-section in Figure 2 of the drawings. As shown in Figure 2, each of the guide bars 10 and 11 is surmounted by a broad, flat flange or plate 12 upon which a slide 13 is slidably mounted under the constraint of splines or feathers 14. Suitable means for holding each of the slides 13 in slidable engagement with the top plate 12 may be provided by means of a clamping plate 15 which may be secured in positive engagement with the flange or plate 12 by means of a cap screw 16. Each of the slides 13 is provided with an upwardly presented bearing lug 17, said bearing lugs being arranged in pairs for rotatably supporting a rotary adjustment shaft 18, said shaft being provided with squared ends 19.

19 for receiving a square socket wrench. Keyed other end upon a driving sprocket wheel 42. As to the shaft 18 are two spur gears 20 which shown in Figure 6 of the drawings, the driving mesh with rack bars 21 mounted on the flange sprocket wheel 42 is provided with an axially or plate 12, the construction being such that extended hub 43 which is journaled in ball 5 bearings 44 in the forwardly presented extension 45 of a blank-creasing support or frame 46 which whenever the shaft 18 is rotated within its is angularly adjustable upon the spaced upper bearings 17, the oppositely arranged slides 13 guide bars 10 in a manner substantially similar whenever the shaft 18 is rotated within its to that of the lower blank-creasing supports 22. The construction for this purpose is clearly 10 invention contemplates four laterally spaced shown in Figure 2, a detailed description of the upper creasing units and a corresponding number of lower creasing units for forming creases in a blank B which has previously been provided with slots b along opposite edges of the blank, 15 said creases being formed between the adjacent inner ends of the slots b. Each of the lower blank-creasing units is provided with a laterally adjustable support 22 of the form shown in Figure 2, said support being provided with 20 downwardly presented branches 23 with base flanges 24 resting upon the oppositely arranged slides 13. As shown in Figure 7 of the drawings, the flanges 23 of the support 22 are provided with openings 25 and 26 for accommodating 25 the shaft 18 which extends through said openings and permit a limited angular adjustment of the support 22 with respect to the shaft 18. For this purpose, the left-hand base flange 24 of the support 22 is provided with a circular 30 opening 24a of larger diameter than the shank of a cap screw 27 which secures the base flange 24 to the slide 13 in any adjusted position of the support 22. The right-hand flange 24 of the support 22 is secured to the corresponding 35 slide 13 by means of a cap screw 28 which passes through a circular hole in the base flange 24 of the support 22 with just sufficient play to permit a slight angular movement of the support 22 about the axis of the cap screws 28. It is by 40 means of this angular adjustment of the several blank-creasing supports that the graded angular arrangement of the blank-creasing units shown in Figure 3, is provided for. Referring now to Figure 5 of the drawings, each of the 45 lower supports 22 is provided with a horizontal flange 29 and a vertical flange 30. Threaded into the horizontal flange 29 at spaced intervals as shown in Figure 2, are a plurality of set screws 31 which may be secured in adjusted 50 positions by check nuts 32, said set screws being adapted to impinge upon the lower edge of an elongated block or carrier frame 33 for a series of creasing members to be presently described. Threaded into each of the frames or 55 blocks 33 are a series of cap screws 34 by means of which said blocks 33 may be secured to the flanges 30 in any adjusted position, suitable allowance for the angular adjustment of the blocks 33 being provided for by slots 30a which 60 permit a limited movement of the cap screws 34. As shown in Figure 5 of the drawings, each of the creaser frames or blocks 33 is provided with a central longitudinal slot for the reception of a series of creasing members. Each 65 creasing member is carried by a pintle 35. Keyed to each of the pintles 35 is a race disk 36 for the ball bearings 37 of a blank-creasing ring 38. The creasing ring 38 is thus arranged to 70 cooperate with the groove 39 in each of a series of channel-shaped creasing members 40 which, as shown best in Figure 2, are linked together in the form of an endless chain. Each of said endless chains may be suitably mounted at one 75 end upon a carrier sprocket wheel 41 and at its other end upon a driving sprocket wheel 42. As shown in Figure 6 of the drawings, the driving sprocket wheel 42 is provided with an axially extended hub 43 which is journaled in ball bearings 44 in the forwardly presented extension 45 of a blank-creasing support or frame 46 which is angularly adjustable upon the spaced upper guide bars 10 in a manner substantially similar to that of the lower blank-creasing supports 22. The construction for this purpose is clearly 80 shown in Figure 2, a detailed description of the same being rendered unnecessary by the foregoing description of the adjustments for the lower supports 22. Referring now to Figure 1 of the drawings, the blank-feeding, -slitting, and -creasing machine in which my invention has been presently embodied, is shown in close-up relation to a spur gear 47 by means of which power may be transmitted from the second printing unit shown in my above-identified co-pending application Serial No. 669,156. In this close-up position of my present machine, power is delivered by the spur gear 47 to a large spur gear 48 which in turn meshes into a large spur gear 49 for transmitting power to a spur gear 50. Said spur gear 50 meshes into a smaller spur gear 51 on the outer end of a power-transmitting shaft 52, said shaft 52 being journaled in the opposite side plates 8 of the carriage side frames. As shown in Figure 6 of the drawings, 105 a spur gear 53 is keyed to the shaft 52 adjacent to each of the upper creaser support 46, said spur gear 53 being provided with an axially extended hub portion 54 which extends through an opening 46a in the support 46 and is provided 110 on its outer end with a part-spherical journal 55. The journal 55 is adapted to provide an oscillatory bearing support for the frame 46 through a correspondingly formed bearing ring 56 which is constructed in two sections and secured to the lateral surface of the supporting frame 46. It will be understood from this description that an angular adjustment of the creaser supporting frame 46 upon the upper slides 13 in the manner hereinbefore described, 115 will be oscillatably supported from the shaft 52 by the part-spherical bearing between parts 54 and 55. The sprocket wheel shaft 43 carries at one end a driven spur gear 57 which meshes into the driving spur gear 53, the limited angular adjustment of the shaft 43 being accommodated for by a suitable amount of play between the gears 53 and 57. As shown in the right-hand portion of Figure 2, between each creasing 120 ring 38 and the next one in series thereto, is disposed a blank-creasing shoe 58 which is shown detached in Figure 9 of the drawings. Said shoe is presented upwardly from a flat plate 59 provided with screw holes 60 through which screws may be threaded into the bifurcated 125 plates of the creaser support 33. It will be understood from this description that as the depth of the crease increases, the shoes 58 are adapted to prevent the blank from adhering to the creaser rings 35 and to form a substantially 130 continuous support for the material in the blank as it is fed through the creasing mechanism. For this purpose, the upper edges of the creaser shoes 58 are slightly depressed with respect to the upper edges of the creaser rings 38. Suitable means for guiding the blanks smoothly 135 into the intake end of the creasing mechanism, may be provided as follows. Presented rearwardly at one end of the lower creaser support 33 is an integrally formed anvil or guide block 140 145 150

61 which is provided with an inclined upper surface 62 which forms with the entering creaser rings 40 a substantially web-shaped space into which the forwardly presented edges of the successive blanks are projected as they move into the creasing mechanism. Adjustably mounted upon a contracted neck portion of the creaser support, is a bifurcated bracket 63 which may be adjusted vertically by a screw 64 and secured in said position by a set screw 65. Journalled in the bracket 63 is a gage roll 66 which may be moved closer to or farther from the lower edge of the endless creaser chain 40 for the purpose of bringing the blank into snug feeding engagement with the lower edge of the endless chain creaser 40 prior to its progress through the gradually lessening space between said creaser belt and the successive blank creasing rings.

In a machine of the character described above, it is important that the blanks which are fed successively into the creaser mechanism be kept in proper registry in respect to operations previously performed on the blanks and in respect to the creasing operations which are to follow. For this purpose, suitable feed rolls are provided which may be adjusted to give the correct pressure on blanks of different thicknesses for maintaining said blanks in predetermined timed relation to the operations of successive parts. As shown in Figure 1 of the drawings, the spur gear 48 meshes into a spur gear 67 on the end of a combined slitter and feed roll shaft 68. The spur gear 67 drives a pinion 69 on one end of a cross-shaft 70, power being delivered from the pinion 69 to a spur gear 71 on a lower feed roll shaft 72. On the far end of the cross-shaft 70 is keyed a spur pinion which is similar in construction to and meshes with an idler spur pinion 73, said pinion 73 being in mesh with a spur gear 74 which is keyed to the far end of an upper feed roll shaft 75. The spur gear 73 also meshes into a spur gear 76 on the far end of an upper feed roll and slitter shaft 77. Intermeshing with the spur gear 67 and a spur gear 78, is an idler pinion 79. The spur gear 78 is keyed to the near end of a lower feed roll shaft 80. Meshing with the spur gear 78 is a spur pinion 81 which drives an upper pinion 82, said pinion 82 being in mesh with a spur gear 83 on an upper feed roll shaft 84. It will be understood from this description of the power transmission to the several feed rolls that a vertical adjustment of the upper feed roll shafts 75, 77 and 84 can be accomplished without materially disengaging any of the driving gears since the driven gear on each of said upper feed rolls moves tangentially on the gear by which it is driven in the vertical direction of adjustment. The upper feed roll shaft 75 may be adjusted by means of a hand wheel 85 which operates through a spur gear connection 86 for raising and lowering said feed roll shaft. A similar adjustment operated by a hand wheel 87 may be adapted to raise and lower the feed roll and slitter shaft 77. A hand wheel 88 may be similarly employed for imparting a vertical adjustment to the feed roll shaft 84. As shown in the lower right-hand corner of Figure 1, a locking bolt 89 may be provided with a rack 90 engaged by a spur gear 91 on a shaft 92 which may be oscillated by a hand lever 93 for throwing the bolt 89 into and out of a socket 94 when the blank-creasing machine is in operating connection with the second printing couple as referred to above.

75 I claim:—

1. In creasing mechanism of the character described, the combination of opposed lines of blank-creasing members, the blank-creasing members of one line being provided with tongues and the blank-creasing members of the other line being provided with grooves, of a gage roll adjustable with and relatively to one line of said blank-creasing members in respect to the other line of said blank-creasing members. 80

2. In a machine for producing parallel scorings, the combination of a plurality of sets of opposed lines of tongue and groove members, of a gage roll movable with one line of said members towards and away from the other line of said members, said gage roll being further adjustable towards and away from said other line of said members and relatively to the first-mentioned line of members. 90

3. In creasing mechanism, the combination of opposed lines of creasing members, the members of one line being provided with tongues and the members of the other line being provided with grooves, of a power shaft for driving one line of said creasing members, a carrier frame for the last-mentioned line of creasing members, a gear 95 non-rotatably mounted on said power shaft and oscillatably bearing on said carrier frame, and a gear rotatable on a fixed axis with respect to said carrier frame for transmitting power to the last-mentioned line of creasing members, said 100 fixed axis gear being permanently in mesh with the gear on the power shaft. 105

4. A scoring mechanism comprising cooperating opposed lines of scoring members, one of said lines being in the form of a series of rolls rotatable about fixed axes spaced apart in the direction of travel of a blank which is to be scored and a series of scoring shoes respectively interposed between successive pairs of said rolls and fixed in respect to the fixed axes of said 110 rolls. 115

5. In a machine for producing parallel scorings, the combination of a plurality of cooperating opposed lines of scoring members, with means permitting bodily shifting of said sets 120 sidewise with reference to one another, a pair of positively driven feed-rolls geared together to rotate in unison with each other and having positively geared connections with one line of said opposed lines of scoring members, and an 125 idler gage roll interposed between said feed-rolls and the other line of said opposed lines of scoring members, said idler gage roll being adjustable vertically towards and away from the line of scoring members geared to said feed-rolls. 130

6. A scoring machine of the character claimed in claim 5, in which one feed roll which is adjustable vertically is provided with a gear and in which an idler gear meshes therewith with the feed-roll gear in a tangential plane substantially 135 parallel to the plane of movement of the adjustable feed-roll.

7. A scoring machine of the character claimed in claim 5, in which the other line of said scoring members comprises a series of spaced rolls 140 adapted to operate upon a blank in the common plane of operation of said feed-rolls, shoes being interposed between successive rolls, and in which said scoring rolls and shoes are movable together towards and away from said common plane of 145 operation of the feed-rolls.

8. In a creasing machine of the character described, the combination with a carriage provided with laterally spaced side frames, a pair of lower transverse guide bars rigidly uniting 150

- said side frames at the bottom, a pair of upper transverse guide bars rigidly uniting said side frames at the top, a plurality of laterally spaced upper creaser units slidably suspended from said 5 upper transverse guide bars, means for arranging said upper creaser units in graded angular relations to each other, a plurality of laterally spaced lower creaser units slidable laterally on said lower transverse guide bars, means for arranging 10 said lower creaser units in graded angular relations to each other, a plurality of pairs of feed-rolls journalled in said side frames for delivering blanks to said creaser units, and a permanent gearing train for driving said feed-rolls 15 and some of said creaser units, said gearing train including a gear movable by the movement of said carriage into and out of geared connection with a machine which delivers blanks to said feed-rolls.
- 20 9. A creasing machine of the character claimed in claim 8, in which one creaser unit of each cooperating pair comprises an endless chain of creasing members, sprocket wheels for driving said endless chain, a spur gear rigidly united 25 to one of said sprocket wheels, a carrier frame for the creaser unit, and in which a power shaft journalled in said side frames and driven by said permanent gearing train is provided with a gear permanently in mesh with the first-mentioned 30 spur gear.
10. A creasing machine of the character claimed in claim 8, in which one creaser unit of each cooperating pair comprises an endless chain of creasing members, sprocket wheels for 35 driving said endless chain, a spur gear rigidly united to one of said sprocket wheels, a carrier frame for the creaser unit, and in which a power shaft journalled in said side frames and driven by said permanent gearing train is provided with 40 a gear permanently in mesh with the first-mentioned spur gear, said power shaft gear being provided with an extension hub which articulately engages said carrier frame.
11. In a creasing machine of the character 45 described, the combination with a fixed creaser frame, a power shaft journalled therein, laterally spaced creaser units slidably mounted on said fixed creaser frame and angularly adjustable in respect thereto, a driven shaft journalled 50 on an axis fixed in respect to each creaser unit, articulated gears keyed respectively to said power and driven shafts, said driven shaft being provided with a journalling support which partakes of the angular adjustments of the creaser 55 unit corresponding thereto, a ball and socket connection between said journalling support and the gear on said power shaft corresponding thereto, and other creaser units cooperatively arranged respectively to the first-mentioned 60 creaser units.
12. In a creasing machine of the character 65 described, the combination with a creaser frame comprising laterally spaced side frames, a pair of lower transverse guide bars rigidly uniting said side frames at the bottom and a pair of upper transverse guide bars rigidly uniting said carriage side frames at the top, of a plurality of laterally spaced upper creaser chain supports 70 slidably suspended from said upper transverse guide bars, an endless creaser chain movable on each of said upper creaser chain supports, a sprocket drive shaft journalled in each upper creaser chain support for driving said creaser chain, a power shaft journalled in said laterally 75 spaced side frames, said upper creaser chain supports being adjustable angularly with respect to the axis of said power shaft, means for articulately supporting each of said upper creaser chain supports from said power shaft, articulated gearing for connecting each of said sprocket drive shafts to said power shaft, a plurality of laterally spaced lower creaser supports 80 slidably laterally on said lower transverse guide bars, means for adjusting said lower creaser supports on said lower transverse guide bars, and means for angularly adjusting each of said lower creaser supports with respect to said lower transverse guide bars. 85
13. In a creasing machine of the character 90 described, the combination with a creaser frame comprising laterally spaced fixed side frames, upper transverse guide bars rigidly uniting said side frames, and lower transverse guide bars rigidly uniting said side frames, of laterally spaced creaser chain supports slidably mounted on said upper transverse guide bars, an endless creaser chain and sprockets therefor mounted on each of said creaser chain supports, said creaser chain supports being angularly adjustable with respect to said upper transverse guide bars, a power shaft journalled in the fixed side frames of said creaser frame, said creaser supports being provided with openings through which said power shaft extends, a sprocket shaft 95 journalled in each creaser chain support, one of said sprockets being keyed thereto, a gear keyed to said sprocket shaft, a gear keyed to said power shaft adjacent to each creaser chain support, the last-mentioned gear being permanently in mesh with the gear on said sprocket shaft and having an extended hub extending through the opening in the adjacent creaser chain support, a ball and socket joint between said extended hub and said adjacent creaser 100 chain support, and lower creaser units mounted 105 on said lower transverse guide bars. 110
14. In a creasing machine of the character 115 described, the combination with laterally spaced fixed side frames, of a carriage movable longitudinally on said side frames, said carriage comprising side frames respectively movable endwise on said fixed side frames, a pair of lower transverse guide bars rigidly uniting said movable side frames of the carriage at the bottom, 120 a pair of upper transverse guide bars rigidly uniting said movable side frames of the carriage at the top, a plurality of laterally spaced upper creaser chain supports slidably suspended from said upper transverse guide bars, an endless creaser chain 125 movable on each of said upper creaser chain supports, a rotary shaft extending longitudinally of each creaser chain support, a rack bar carried by each of said upper transverse guide bars and extending past said rotary shafts, gears keyed to each of said rotary shafts and meshing with said rack bars respectively, a plurality of laterally spaced lower creaser supports 130 slidably laterally on said lower transverse guide bars, a rack bar mounted on each of said lower transverse guide bars, a rotary shaft extending longitudinally of and journalled in each of said lower creaser supports, gear pinions keyed to each of the last-mentioned rotary 135 shafts and respectively meshing with the last-mentioned rack bars, a plurality of creasing rolls journalled about axes spaced longitudinally 140 with respect to and cooperating with said creaser chain, an adjustable support for said creaser chain, 145 an adjustable support for said creaser chain, 150

- rolls for positioning said creaser rolls in graded proximity to the lower run of said endless creaser chain, and means for angularly adjusting each of said adjustable supports in a horizontal plane. 80
15. In a creasing machine of the character described, the combination with a frame provided with spaced transverse guideways, of slides movable on said guideways, each of said 10 slides being provided with a bearing lug, a rack bar mounted on each of said transverse guideways adjacent to the paths of said slides, a rotary shaft journalled in said bearing lugs, said rotary shaft being provided with gears respectively in mesh with said rack bars for moving said slides in unison, a creaser support pivoted at one end to one of said slides and having its other end connected to the other of said 15 slides by a pin and slot connection, and blank-creasing means mounted on said creaser support. 20
16. In a machine of the character described, the combination with laterally spaced side frames, a top frame, and a bottom frame, upper 25 and lower transverse guides mounted on said top and bottom frames, a plurality of upper slides reciprocable laterally in pairs on said upper transverse guides, a plurality of lower slides reciprocable laterally in pairs on said 30 lower transverse guides, means for shifting each pair of slides in unison on their respective transverse guides, an upper creaser support pivotally mounted on one slide in each pair of upper slides and having a pin and slot connection with the other upper slide of that pair, a lower creaser support pivotally mounted on one slide in each pair of lower slides and having a pin and slot connection with the other lower slide of that pair, cooperating pairs of upper and lower 35 creaser units mounted on said creaser supports, a power shaft journalled on a fixed axis in said side frames and a driving gear splined to said rotary shaft for one of said creaser units in each cooperating pair. 40
45. 17. In a machine of the character described, the combination with upper and lower transverse guides, of a plurality of upper slides reciprocable laterally in pairs on said upper transverse guides, a plurality of lower slides reciprocable laterally in pairs on said 50 lower transverse guides, a rotary shaft journalled in each pair of said upper and lower slides, a rack bar mounted on each of said upper and lower transverse guides, gear pinions keyed to each of said rotary shafts and meshing with said rack bars respectively, an upper creaser support mounted on each of said creaser supports, said 55 creaser units being arranged in cooperating pairs of upper and lower creaser units, a power shaft journalled on a fixed axis, and a driving gear splined to said rotary shaft for each of said upper creaser units, said driving gear being provided with a hub in movable engagement with the adjacent creaser support. 60
65. 18. In a machine of the character described, the combination with laterally spaced guides, of a carriage reciprocable on said laterally spaced guides, said carriage comprising laterally spaced side frames, a top frame, and a bottom frame, upper and lower transverse guides mounted on 70 said top and bottom frames, a plurality of upper slides reciprocable laterally in pairs on said upper transverse guides, a plurality of lower slides reciprocable laterally in pairs on said 75 lower transverse guides, a rotary shaft journalled in each pair of said upper and lower slides, a rack bar mounted on each of said upper and lower transverse guides, gear pinions keyed to each of said rotary shafts and meshing with said rack bars respectively, an upper creaser support pivotally mounted on one slide in each pair of upper slides and having a pin and slot connection with the other upper slide of that pair, a lower creaser support pivotally mounted on one slide in each pair of lower slides 80
